E. Barrett.

Scythe

Patented Jun. 16, 1830.

June 16, 1836

Ezra Barnatt of Warner county of Merrimack, State of New Hampshire.

Letters Patent

The schedule referred to in these Letters Patent, and making part of the same, containing a description in the words of the said Ezra Barnatt himself of his improvement in the scythe:

To all, to whom these Presents shall come

Bid know, that I, Ezra Barnatt of Warner, in the county of Merrimack, and state of New Hampshire, have invented a new and useful improvement in scythes, as it respects a crook in the blade from 8 to 10 inch at the heel and extending the edge of the scythe at the heel to the wing, and in the shape and length of the shank, and shape of the claw, the following is a full and exact description thereof:—That

the crook on the blade of the scythe from 8 to 10 inch at the heel, similar to the gathering part of a sickle, so as to cut the grass clean and easy as it gathers at the heel; with this crook at the heel of the scythe, the forepart of the grass is cut from the middle to the heel, exactly reverse to that of the common straight heel scythe.

The edge of the scythe is also extended at the heel to the wing so as to prevent the grass escaping without the scythe.

The shank from the heel of the scythe to the claw, is from 1, 1/2 to 2 1/2 inch long, flat on the upper side and an oval round upon the under side similar to what is called a flat half round file, with a regular taper from the heel to the claw, as it respects both the width and thickness, so as to admit the wing to pass over the shank to the heel without the necessity of cutting away the scythe to injure it, the shank being thus formed will exactly fill the space made upon the scythe to receive it, and thereby completely fill the wing so as not to need or require a wedge to make it perfectly tight and firm upon the scythe, thus the wing and heel of the scythe are both preserved from injury by the breaking and fracture of a wedge.

The shank being of the length above described, requires but a small claw, which is about one quarter of an inch in diameter, half

an inch in length and round, and a little tapering from the shank to the end, which gives another advantage to the scythe, as it is less injured by cutting off the wood in making a hole to receive the claw, and is much less exposed to damage by putting on and taking off the scythe, besides the round claw does not weaken the scythe so much as one that is square.

It is a well known fact, that that part of the scythe, where the claw enters is almost uniformly the first that fails, this is owing in part to the shortness of the shank of the scythe, and the length of it at the claw, and partly to the improper size and shape of the claw. By comparing any model with the scythes now in use, the utility of the above described improvement will I think clearly appear.

This improvement may be applied with equal advantage to Farwell's Patent common scythes, or to any others now manufactured. There has been some attempts to introduce a crooked blade scythe, but the crook was not at the heel, but from 6 to 12 inches from it, and the operation of it was entirely different, as was also the shape and effect produced by it.

That I claim above as my own invention and improvement in scythes, not known or used before my application, is a crook in the blade from 8 to 10 inches at the heel, and reducing the edge of the scythe at the heel to the ring, and in the shape & length of the shank, and shape of the claws as above described - in the above specification.
